US00D519280S

(12) **United States Design Patent** (10) Patent No.: **US D519,280 S**
(45) Date of Patent: **** Apr. 25, 2006**

(54) **COLLAPSIBLE STRUCTURE**

(75) Inventors: **Michael S. Kellogg**, Oconomowoc, WI (US); **Dean B. Krotts**, Milwaukee, WI (US)

(73) Assignee: **Bajer Design & Marketing, Inc.**, Pewaukee, WI (US)

(**) Term: **14 Years**

(21) Appl. No.: **29/179,677**

(22) Filed: **Apr. 11, 2003**

(51) LOC (8) Cl. **03-01**

(52) U.S. Cl. **D3/305; D32/37**

(58) Field of Classification Search ..... D3/304-315; D32/37; 220/485, 486, 487, 9.1, 9.2, 9.3; 383/4; 217/43 R; 206/203, 215, 307.1, 555, 206/561, 557, 822

See application file for complete search history.

(57) **CLAIM**

The ornamental design for a collapsible structure, as shown and described.

DESCRIPTION

FIG. 1 is a perspective view of a first embodiment of the collapsible structure;

FIG. 2 is a top plan view thereof;

FIG. 3 is a bottom plan view thereof;

FIG. 4 is a front elevation view, the rear elevation view being identical;

FIG. 5 is a right side elevation view, the left side elevation view being identical;

FIG. 6 is a perspective view of a second embodiment of the collapsible structure;

FIG. 7 is a top plan view thereof;

FIG. 8 is a bottom plan view thereof;

FIG. 9 is a front elevation view, the rear elevation view being identical; and,

FIG. 10 is a right side elevation view, the left side elevation view being identical.

1 Claim, 4 Drawing Sheets

UNITED STATES PATENT AND TRADEMARK OFFICE
CERTIFICATE OF CORRECTION

PATENT NO. : Des. 519,280 S
APPLICATION NO. : 29/179677
DATED : April 25, 2006
INVENTOR(S) : Michael S. Kellogg and Dean B. Krotts

Page 1 of 1

It is certified that error appears in the above-identified patent and that said Letters Patent is hereby corrected as shown below:

On the Title Page under "Other Prior Art" insert the following references:

--"Magic Maaze" Frontgate Mail-Order Catalog, Summer 1995, pg. 32

Play Hut Brochure, date unknown.--

Signed and Sealed this

Twenty-seventh Day of March, 2007

A handwritten signature in black ink, appearing to read "Jon W. Dudas". The signature is written in a cursive style with a large, stylized "D" and "u".

JON W. DUDAS
Director of the United States Patent and Trademark Office
